UNITED STATES PATENT OFFICE.

JOHN C. WALSH, OF PHILADELPHIA, PENNSYLVANIA.

SHOE-SUPPORT.

1,104,396.

Specification of Letters Patent.

Patented July 21, 1914.

Application filed September 8, 1911. Serial No. 848,322.

To all whom it may concern:

Be it known that I, JOHN C. WALSH, a citizen of the United States, residing at Philadelphia, in the county of Philadelphia and State of Pennsylvania, have invented 5 certain new and useful Improvements in Shoe-Supports, of which the following is a specification.

This invention relates to improvements in racks for holding shoes while being shined or polished, and to this end I have devised a simple, inexpensive, and efficient standard arranged to project outwardly of a wall or other support, upon which is removably 15 mounted a shoe holder adjustable to shoes of various sizes.

The object of my invention is to provide a pivotal standard mounted upon a wall, and supporting members for a shoe and the like 20 dependingly carried by said standard or bracket engaging the upper of the shoe to be supported at opposite ends.

This device is provided with a fixed and an adjustable member for suspending a shoe 25 in contradistinction to supporting it upon a solid back, the fixed member engaging the toe end of the shoe and the other member being adjusted in the shoe to assume a position at the rear end of the upper.

With the above and other objects in view 30 my invention consists in the arrangement, combination and details of construction shown in the drawings, and then more particularly pointed out in the appended claims.

Similar reference characters designate similar parts in the respective views, where-
in—

Figure 1 is a side elevation of the device in position for suspending a shoe, Fig. 2 is 40 a top plan view of the device showing one size of a hook member for holding the shoe at a definite angle with respect to the wall. Fig. 3 is an elevational view of the device when in folded position. Fig. 4 is a detail fragmental top plan view of the forward end of the bracket. Fig. 5 is a detail fragmental end elevation of the fixed shoe holding member, and Fig. 6 is a bottom plan view of the toe member.

Mounted on a wall or other suitable support is a suitable block 1 which is vertically disposed and secured thereto by any suitable means. Staples or hook members 2 and 3 are carried near each end of the block 1 45 forming a bearing for a pintle 4 braced diagonally at 5 to a preferably horizontally

disposed member 6 mounted on the body of said pintle between the hook members 2 and 3, the brace 5 restraining endwise movement and holding said pintle against vertical displacement. The member 6 is formed with a longitudinal slot 8, and a recessed guideway 7 forming guiding walls 9 and 10 respectively, a block 11 is slidable in said recess, a screw having its head spanning the slot 8 of narrow width, being tapped through the block 11, and engaged exteriorly of the member or bracket 6 by a thumb-nut 12. Dependingly and integrally carried by the block 6 is a bar 13 terminating in an inclined curvilinear 70 offset 14 upon the extremity of which a boss 15 is formed. The free end of the bracket 6 is formed with a tenon 16 at the inner end of which outwardly project shoulder portions 17 and 17' and at the opposite extremity of 75 which a preferably rounded head 18 is formed having shoulder portions 19 and 19' in alinement with the portions 17 and 17', the inner walls of the shoulder portions being parallel with one another and at right 80 angles to shank or tenon 16.

20 designates a hook shaped member formed at one end with a rectangular recess 21 formed by an offset 22 formed at right angles to its body and terminating in a depending portion 22' parallel to said body, a protuberance or lug 23 being formed upon the offset 22 having an aperture 24 therein. The curved branch 25 of member 20 is arranged to enter the toe end of an upper 90 being attached to independent members 26 and 27 having their edges brought together at 28, a crosspiece 29 formed on member 25 being suitably fastened as by studs 30 to both members 26 and 27 at their bottom 95 portions.

As clearly shown in the drawings each toe member 26 and 27 has preferably horizontal lower surfaces and an upper curved surface 31 rising evenly from opposite edges to form 10 a tapered top tapering from small at the outermost extremity to large at the rear end and from large at the lateral margins to small at the top, the sides of the members 26 and 27 being oppositely slotted at 32 and 105 33 respectively, so that the adjoined bars 34 and 35 of these members will engage and conform to the curve of the inner wall of the toe of the upper, while the bottom marginal strips 36 and 37 respectively, of said members are curved similarly to and arranged to engage the marginal portions of the sole. 110

Each member 26 and 27 is formed at its rear end with suitable lugs 38 and 39 respectively bearing upon transverse lugs 40 on the curved part 25 of member 20 which are formed with a plurality of openings 41 registerable each with a corresponding opening in each member 26 and 27 whereby the latter may be swung on the pivots or studs 30, and secured against movement by cotter pins 42. Secured to the same wall or support and at one side of the block 1 are hooks or staples 43 in which the bill portions 44 of hook members 45 are placed as the opposite free end formed with a rectangular offset 46 is passed through the aperture 24 of the lug 23 of member 20, thereby serving to rigidly hold the bracket 20 at right angles to the walls.

In operation the hook members 45 will be made of various sizes so that the brackets 20 may project in positions at greater or less angles than a right angle. The bracket having been swung or turned on pivots or pins 4 and set in position by means of the brace members 45 the members 13 and 20 may be arranged to engage a shoe upper. The recess 21 of member 20 will be presented over the shank 16 of the bracket 6 and being of the same width therewith, the tenon will enter its mortise snugly and support the curved member 20. The lug 23 through which the offset 46 of member 45 is passed will be at the left of bracket 6 when the sole engaging projection formed by members 26 and 27 is held forwardly of the bracket, but it will be at the right side thereof when said projection is held inturned under said bracket, see Figs. 1 and 3, which denote diametrically opposite positions of said projection thereon. The shoe 48 may be accommodated irrespective as to its size and after the curved projection of member 20 has been passed into the toe end of the upper so that the upper curved surfaces 31 of members 26 and 27 bear against the leather of the toe, as shown in Fig. 1, the member 13 may be adjusted in the shoe in which it has been caused to project. By moving the sliding block 11 in the longitudinal guide recess 7 toward the rear of the shoe 48 the boss 15 of the member 13 will be caused to bear against the rear wall of the upper as shown in Fig. 1. To operate the slide block 11 the thumb screw 12 will be loosened enabling the block 11 to have sliding contact with the walls of said recess. The boss or toe 15 serves to hold the toe end of the upper against displacement. Both shoe engaging members 13 and 20 are removable. It is to be noticed that the members 26 and 27 are formed with extremities which flare so as to form a recess 47. This is for the purpose of enabling the toe members 26 and 27 to be laterally extended each being movable on one of the studs 30 as a pivot, as shown in Fig. 6, so

that if the cotter pins passed through the aperture 41 of the wing 40 and through the corresponding openings in lugs 38 and 39 of said members be removed, the latter may be turned outwardly until the recess 47 is narrowed by the extremities of said members whereupon the said members will be in the position indicated by dotted lines in Fig. 6, then by replacing the cotter pin 42 through the appropriate apertures the toe members will be held in this position; as thus extended the toe projection of member 20 is adapted to engage the sole of the upper correspondingly sized to receive it. Both the openings through which the studs 30 pass and the openings 41 are enlarged in diameter so as to allow play for studs 30 and for the cotter pins passing through lugs 38 and 39 when the toe members are swung laterally.

Numerous modifications may be resorted to in practice from the exact details of construction shown without departing in essence from the principle disclosed.

Having now described my invention, that which I claim to be new and desire to procure by Letters Patent is:

1. A device of the kind described consisting of a bracket, an enlargement formed terminally of said bracket, and a shoe tree comprising an arm formed with an angularly disposed terminal having a lug downwardly turned, and parallel to said arm, said arm being supported on said bracket, said enlargement formed with opposed recesses arranged to receive said arm and its parallel offset.

2. A device of the kind described comprising a bracket, a bearing in which said bracket is pivoted, a member adjustable on said bracket and engaging the heel end of a shoe, an enlargement formed terminally of said bracket, a shoe tree comprising an arm formed with an angularly disposed terminal having an offset parallel to said arm, said arm being supported on said bracket, said enlargement being formed with opposed recesses arranged to receive said arm and its parallel offset, an integral lug formed on said arm extending laterally of said bracket, and a brace arranged to be pivotally connected to a wall and removably connected to said lug to hold said bracket in position.

3. In combination an arm, two sections arranged to support the toe end of a shoe, each of said sections having a rectilinear edge arranged normally to abut with that of its mate, the rectilinear edge of each section formed with an inwardly sloping surface at one end thereof whereby said sections may bodily rock on each other, a cross-piece formed integrally at one end of said arm, each section being pivotally connected at one end to one end of said cross-piece, lugs formed upon said arm upon one of which

the opposite end of each section is slidable, and means engaging said lugs and said sections arranged to hold said sections in set position.

- 5 4. The described device consisting of a pivotally mounted bracket having an enlarged outer end and a longitudinal slideway, a shoe tree on the end of said bracket, a shoe heel engaging member slidable in said 10 slideway, means for holding said member in fixed position, and means for holding said bracket rigidly projected, said tree consisting of an arm having its upper end returned whereby it may engage said bracket, said

bracket having recesses for engagement with 15 said arm and returned portion, said arm having a right angular portion, the outer end of which is T-shaped, toe engaging members pivoted to said outer end, and opposing lugs inwardly of said end over which 20 said members are movable and means whereby said members may be fixed to said lugs.

In testimony whereof I affix my signature in presence of two witnesses.

JOHN C. WALSH.
